PADDING SUPPORT

Frank B. Williams and Harold E. Williams,
Carthage, Mo.

Application December 13, 1940, Serial No. 369,960

9 Claims. (Cl. 245—8)

Our invention relates to improvements in padding supports which are adapted to be disposed upon the upper ends of coiled springs of seats of cars, chairs, lounges and like articles, or over the front ends of the springs of backs of such articles, to keep the padding of the upholstering from getting between or into said springs.

One of the objects of our invention is the provision of a novel padding support of the nature stated, which is simple, cheap to make, is strong, durable and not likely to get out of order, which is easily applied in its operative position, and which is efficient in its operation.

Another object of our invention is the provision of a novel method of making our improved padding support.

The novel features of our invention are hereinafter fully described and claimed.

In the accompanying drawing, which illustrates our invention,

Fig. 1 is a plan view of one of our improved padding supports.

Fig. 2 is a plan view, showing our padding support in process of construction, and portions of mechanism, which may be employed in such construction, shown extended across the longitudinal strands or cord-like members of the support.

Fig. 3 is an enlarged cross section on the line 3—3 of Fig. 2.

Fig. 4 is an enlarged cross section on the line 4—4 of Fig. 2.

Fig. 5 is an enlarged section on the line 5—5 of Fig. 2.

Fig. 6 is an enlarged section on the line 6—6 of Fig. 2.

Fig. 7 is a reduced cross section showing one of our padding supports with the eyes of one of the transverse members partly completed.

Fig. 8 is a view similar to Fig. 7, showing the eyes completed.

Similar characters of reference designate similar parts in the different views.

Our improved padding support comprises spaced apart pliable or flexible longitudinal parallel members, 1, preferably of cord-like form, as cords made of twisted paper, or common cords, at the outer sides of which respectively are anchoring members, 2, preferably comprising cord-like members similar to the members 1, spaced from and parallel with the members 1.

3 designates transverse members, spaced apart and extended through the intermediate members 1, and being, preferably, resilient metal wires which are of less diameter than the members 1,

and are hard enough to perforate and be extended through the softer pliable members 1.

The transverse members 3 each has holding engagement with the longitudinal outer members 2, effected, preferably, by providing the end portions respectively of the members 3 with eyes 4, as shown, which eyes hold the members 3 from endwise displacement. The eyes 4 may be of a diameter permitting in some cases, where desired, movement lengthwise of the members 2, but in most cases the eyes 4 are in clamping engagement with the members 2, to prevent endwise movement along the outer members 2.

In the making of the padding supports, they 15 may be made in long lengths, of desired widths, and afterward transversely into lengths suitable for the purposes in view.

In the making of the padding supports, the longitudinal members 1 and 2 may be drawn from 20 rolls, not shown, and the transverse members 3 successively drawn from a roll, not shown, inserted transversely through and perforating therewith the intermediate members 1, so as to project beyond the outer members 2. The wire 25 constituting the member 3, so withdrawn, is then severed, and the end portions of the severed member formed into the eyes 4 around the outer longitudinal members 2, and, when desired, with the eyes 4 formed to embrace the members 2 in tight non-slip engagement therewith.

A modification in the method of manufacture is shown in Fig. 7, in which the end portions of a transverse member 3 are formed respectively in two hooks 5, into which the outer longitudinal members 2 are laterally inserted, after which the hooks 5 are closed into eyes 4, which embrace the members 2, as shown in Fig. 8.

Or the eyes 4 may have the outer cord-like members 2 inserted respectively through the eyes 4, and the eyes then crimped into non-slip engagement with the members 2.

The preferred method, however, is that described as forming the eyes 4 around the members 2 into tight non-slip engagement with the members 2, after the transverse members 3 have been extended through the intermediate members 1.

In the drawing is shown portions of mechanism adapted to make our improved padding supports.

This mechanism comprises an upper transverse member 6 of metal disposed upon, and parallel therewith, a metal member 7.

The adjacent sides of the members 6 and 7 are provided with registering arcuate recesses 8 and 9 respectively, disposed in a horizontal row to

form transverse holes through which are drawn the intermediate members 1.

In operation, the wire is drawn from a reel, not shown, or from a roll of wire, and forced through a longitudinal hole intersecting diametrically the holes formed by the recesses 8 and 9, said longitudinal hole being formed by two registering longitudinal arcuate recesses 10 in the adjacent sides of the members 6 and 7.

The transverse wire is forced through and perforates the intermediate members 1 to a stop member 11, at the right of the members 6 and 7, as viewed in Figs. 3 and 4. The wire is then severed at the proper distance from the adjacent ends of the members 6 and 7, by shear blades 12, and 13, Figs. 3 and 4.

At opposite ends of the members 6 and 7 are two cam wheels 14 and 15 having respectively two cams 16 and 17. The cam wheels 14 and 15 have each a shaft 18 rotatable in a supporting member 19, and each of said wheels has through it an axial hole through which is adapted to freely pass the adjacent longitudinal cord-like member 2, Figs. 5 and 6. The shafts 18 have respectively fastened on them two pinions 20 respectively meshing with two racks 21, which are simultaneously reciprocated in opposite directions, by any suitable means, not shown.

As shown in Fig. 4, the transverse wire 3 when fed through the longitudinal cord-like members 1, as has been described, passes under the cams 16 and 17 and above the longitudinal cord-like members 2. After the wire 3 has been severed by the shear blades 12-13, the racks 21 are moved in opposite directions, thereby through the pinions 20, rotating the cam wheel 14 counterclockwise, and the cam wheel 15 clockwise. The cams 16 and 17 then form the projecting end portions of the wire 3 around the longitudinal cord-like members 2, to form eyes 4 at the ends of the wire 3, as shown in Fig. 3. By slightly varying the distance of the cams 16-17 from the axes of the cam wheels 14-15, the cams 16 and 17 may be made to vary the diameters of the eyes 4, so that they will tightly clamp the eyes in non-slip engagement with the longitudinal members 2, or, when desired, embrace them loosely.

After forming the eyes 4 around the members 2, the members 6 and 7 are moved vertically apart, to free the wire 3, and the longitudinal members 1, between them. The longitudinal members 1 and 2 and the transverse wires 3 are then advanced to the left, as viewed in Figs. 5 and 6, and in the direction indicated by the arrow in Fig. 2, the proper distance, after which the members 6 and 7 are returned to their operative position, shown in Figs. 3 and 4, and the racks 21 are retracted to position the cams 16 and 17 in their original upper position, shown in Fig. 4. This completes a cycle of operations.

The operations, just described, are repeated to form a net work of considerable length, after which it is severed transversely into padding supports of desired lengths. These supports may be disposed and fastened in operative positions, in any desired manner, upon the tops of coil springs of seats, or against the front ends of coiled springs of backs, and the padding of the upholstering applied thereon. The size of mesh of the padding supports so made is made small enough to prevent the padding entering between or into the springs.

If desired, these padding supports may be used

by themselves, or against fabric strips or sheets, such as burlap, or canvas covering the springs.

In the construction, it is preferred to employ cord-like longitudinal members 1 and 2, made of twisted strips of tough paper, as such members can be readily perforated by the transverse wires 3, and can be tightly gripped by the eyes 4 without damage.

By causing the transverse wires 3 to perforate the intermediate longitudinal members 1 while the wires are being fed, separate perforating of the longitudinal members 1 is avoided, greatly reducing the cost of manufacture.

Other modifications of our invention, within the scope of the appended claims, may be made without departing from the spirit of our invention.

What we claim is:

1. In making a padding support of the kind described, the method consisting in extending spaced apart transverse members transversely through and perforating therewith intermediate ones of spaced apart longitudinal pliable members, and establishing holding engagement of said transverse members with the two outside ones of said longitudinal members.

2. In making a padding support of the kind described, the method consisting in extending spaced apart transverse members transversely through and perforating therewith intermediate ones of spaced apart longitudinal pliable members, and forming portions of each of said transverse members around and into holding engagement with the two outside ones respectively of said longitudinal members.

3. In making a padding support of the kind described, the method consisting in extending spaced apart transverse members transversely through and perforating therewith the intermediate ones of spaced apart longitudinal pliable members, and forming portions of each of said transverse members around and into tight non-slip holding engagement with the two outside ones respectively of said longitudinal members.

4. In making a padding support of the kind described, the method consisting in extending spaced apart transverse members transversely through intermediate ones of spaced apart longitudinal parallel pliable members, forming hooks of the end portions of each of said transverse members, disposing the two outside ones of said longitudinal members in the adjacent hooks, and forming said hooks into eyes respectively tightly embracing the adjacent longitudinal members.

5. In making a padding support of the kind described, the method consisting in extending spaced apart transverse members transversely through longitudinal parallel pliable members, forming eyes in said transverse members at the outer side of and spaced from the two outer ones of said longitudinal members, and extending two longitudinal pliable members through the two rows of eyes respectively so formed.

6. A padding support of the kind described comprising longitudinal spaced apart pliable members, and transverse spaced apart members extending through intermediate ones of said longitudinal members and partly encircling and having holding engagement with the two outside ones of said longitudinal members.

7. A padding support of the kind described comprising longitudinal parallel pliable members, spaced apart, and spaced apart transverse members extending through intermediate ones of said longitudinal members and having eyes respec-

tively embracing and having tight non-slip engagement with the two outside ones of said longitudinal members.

8. A padding support of the kind described comprising longitudinal pliable spaced apart cord-like members, two pliable members at the outer sides respectively of said cord-like members and spaced from and parallel therewith, and spaced apart transverse members extending through said cord-like members and having holding engagement with said two pliable members.

10

5

9. A padding support of the kind described comprising longitudinal, parallel, pliable spaced apart cord-like members, and transverse spaced apart flexible transverse members extending through intermediate ones of said longitudinal members and each having eyes through which the two outside ones of said cord-like members extend and are held in non-slip engagement.
